(57) **CLAIM**

The ornamental design for a foldable car armrest as shown and described.

DESCRIPTION

FIG. 1 is a front, right and top perspective view of a foldable car armrest, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 2; and, FIG. 11 is a rear, left and top perspective view of the foldable car armrest in another state.

The broken lines depict portions of the foldable car armrest that form no part of the claimed design. The dot-dash broken lines in FIGS. 1, 2, 9 and 10 depict the boundaries of the enlargements that form no part of the claimed design.
